UNITED STATES PATENT OFFICE

155,359

DESIGN FOR A POWER-OPERATED PEELING APPARATUS

Harry Pearlman, Syracuse, N. Y.

Application March 26, 1948, Serial No. 145,378

Term of patent 14 years

(Cl. D89—1)

To all whom it may concern:

Be it known that I, Harry Pearlman, a citizen of the United States, residing at Syracuse, in the county of Onondaga and State of New York, have invented a new, original, and ornamental Design for Power-Operated Peeling Apparatus, of which the following is a specification, reference being had to the accompanying drawings, forming part thereof.

Fig. 1 is a rear perspective view of a power-operated peeling apparatus showing my new design;

Fig. 2 is a side perspective view thereof;

Fig. 3 is a front perspective view thereof; and
Fig. 4 is a top perspective view thereof.

I claim:

The ornamental design for a power-operated peeling apparatus, as shown.

HARRY PEARLMAN.
